UNITED STATES PATENT OFFICE.

DAVID L. WINTERS, OF PHILADELPHIA, PENNSYLVANIA.

TWO-CYCLE INTERNAL-COMBUSTION ENGINE.

1,408,329.

Specification of Letters Patent. Patented Feb. 28, 1922.

Application filed September 3, 1920. Serial No. 407,895.

To all whom it may concern:

Be it known that I, DAVID L. WINTERS, a citizen of the United States, residing at Philadelphia, in the county of Philadelphia and State of Pennsylvania, have invented 5 certain new and useful Improvements in Two-Cycle Internal-Combustion Engines, of which the following is a specification.

This invention relates to internal combustion engines of the two-cycle type, and has 10 for its primary object the incorporation of means in the construction thereof to increase the reliability of their operation under excessively throttled or idling conditions.

15 Other objects of this invention will be specifically pointed out herein.

In the operation of a two-cycle internal combustion engine it is practically impossible to secure satisfactory operation under 20 excessively throttled or idling conditions which is not so in the operation of a four-cycle engine.

Upon excessive throttling of a four-cylinder four-cycle engine for idling purposes 25 a substantial vacuum is created in the working end of one of the cylinders at all times. The internal resistance which is thus created in the absence of an operative load, necessitates the use of an effective charge, or one of 30 sufficient volume to secure proper ignition and combustion, and this ensures reliable operation in a four-cycle engine at greatly reduced speed when idling.

In a multiple cylinder two-cycle engine 35 however there are presented not only twice as many power impulses per revolution, but there is no vacuum created in the working ends of the cylinders when idling, such as above described in the operation of a four-

40 cycle engine.

Also, as the crank cases of two-cycle engines are utilized as air or gas pumps, depending upon the location of the carburetor, when the volume of the charge is greatly reduced by throttling, the pumping of air and the internal resistance occasioned thereby is equally reduced, thus presenting substantially no resistance to the movement of the piston under excessive throttled conditions 45 in the absence of an operative load. Due to these conditions and because the inlet ports to the engine cylinders do not remain open nearly as long as in the four cycle type, the engine will race for an instant when the load 50 is removed and then stop, as its speed is not retarded by any internal resistance, while

the passage of fuel to the engine is being very greatly retarded, and thus prevents the entrance of an effective charge upon the racing of the engine.

It is known that a two-cycle engine may be 55 permanently attached to the propeller shaft of a boat and successfully throttled to a very slow speed, for the reason that while the load is greatly decreased by such decrease in speed, the resistance presented by the load to the engine when the charge is excessively throttled, reduces the speed of the engine sufficiently to permit the furnishing of an effective charge thereto.

The operation of a two-cycle engine as above outlined has prevented the successful application of such an engine for vehicle propulsion, and it is a further object of this invention to provide a two-cycle engine with 70 means whereby it is adapted for successful operation for power transmission to vehicles.

This object is obtained by the provision of a slight or comparatively small non-operative load (as contra-distinguished from 75 the load upon the engine during the propulsion of the vehicle) which is to be applied to the engine when the same is idling or running free of the driving mechanism of the vehicle, and therefore operating under excessively throttled conditions. The substitution of this non-operative load for the operative load when idling results in a positive reduction in speed which causes the intake ports of the engine to remain open a sufficient length of time to compensate for the 80 restriction in flow of fuel thereto, thus insuring the furnishing of an effective charge, and the desired reliable operation of the engine.

In order to accomplish the desired results it is intended within the scope of this invention to retain or apply the non-operative load referred to internally of the engine by suitable means hereinafter described.

With the foregoing and other objects in view as will be apparent, this invention consists in the peculiar construction and combination of the various related elements of a two-cycle engine as hereinafter described and more particularly pointed out in the appended claim.

Referring to the accompanying drawings forming a portion of this specification and in which the same reference numerals indicate the same parts wherever used,

Fig. 1 is a side elevation of a multiple

cylinder two-cycle engine illustrating the preferred embodiment of this invention as applied thereto;

Fig. 2 is a vertical section on line 2—2 of Fig. 1;

Fig. 3 is a modified form of the device as applied to a single cylinder two-cycle engine; and

Fig. 4 is a horizontal section on line 4—4 of Fig. 3.

Referring particularly to Figs. 1 and 2, 6 and 7 designate the engine cylinders mounted upon crank cases 8 in which is housed the crank shaft 9 carrying connecting rods 10 which are driven in the usual manner by pistons 11.

A carburetor 12 of any suitable type is adapted to supply the mixture to the crank cases 8 by means of an intake manifold 13 having intake ports 14 and 15 of usual construction and controlled by a throttle valve (not shown) by a lever 16 of any approved type.

Suitably mounted at 17 on the cylinder 7 is the control lever 18 adapted to be adjustably held in position by means of a quadrant 19, the lever 18 being extended to form a foot 20 which carries a rod 21 to which is pivotally connected at 22 a second rod 23 which extends downwardly through an eye 24 formed in the throttle lever 16. The rod 23 is provided with an adjusting nut 25 at a point directly above the eye 24 of the lever 16, and also carries below the eye 24 a spiral spring 26 the upper end of which bears against the eye 24 and is adapted to be tensioned thereagainst by means of an adjusting nut 27 threaded upon the rod 23. The rod 23 terminates in a pivotal connection 28 the purpose of which will be hereinafter explained.

The crank cases are in controlled communication with each other through the medium of a piping connection 29 carrying a plug valve 30 adapted to control the communication between said crank cases and having an operating lever 31 which is connected to the pivotal connection 28 of the rod 23 heretofore described.

Adjacent the throttle lever 16 and so positioned as to adjustably limit the upward movement thereof is a stop 32 vertically adjustable within its support 33.

Means, indicated as a whole by 63, are provided to connect the engine with a driving shaft.

The operation of the construction shown in Figs. 1 and 2 is as follows:

While operating under ordinary load conditions the throttle lever 16 is lowered by means of the lever 18 to effect an opening of the throttle valve (not shown) and through the medium of the rod 23 and the lever 31, the plug valve 30 is closed, and 65 operates in a closed position until such

time as the throttle is again moved to a comparatively closed position for idling by the lever 18. When this condition of operation occurs, the plug valve 30 begins to open at the point where the throttle lever 16 engages the stop 32, this stop preventing a further closing of the throttle valve. 76

This opening of the plug valve 30 permits the alternate wasting of the mixture under pressure in the crank cases 8 from one crank case to the other through the connection 29, since the pistons operating therein are on opposite strokes. 75

The spring 26 operates to close the throttle valve as shown, and also permits a further movement of the rod 23 through the eye 24 after the lever 16 has engaged the stop 32 to effect a further opening of the plug 30, thus increasing the waste of pressure above referred to. 80

In the construction illustrated in Figures 3 and 4 the single cylinder is indicated by the numeral 34, the segment 19, lever 18 and rod 21 with its pivotal connection 22 being of the same construction as heretofore described. Pivotal connected at 22 to the rod 21 is a second rod 35 which passes through the eye 24 of the throttle lever 16 controlling the throttle valve 36 in the intake port 36'. The adjusting nut 25 is located 90 as in Figs. 1 and 2, as also are the spring 26, adjusting nut 27, and the stop 32 with its support 33. 95

Rod 35 terminates in a member 37 having a vertical side face 38, which is beveled at 39, as shown. An outwardly opening valve 40 normally held closed by a spring 41 carried by the valve stem 42 is located in the wall of the crank case 8 at such a point that the stem 42 will engage either the face 38 or the bevel 39 of the member 37 according to the vertical position of the member 37 under control of the lever 18 through the operation of rods 21 and 35 thereby. 105

The valve stem 42 is housed in a cage 43 having an arm 44 providing a slidable mounting for the member 37. The carburetor 45 is located in the usual position for two-cycle engines of the air pump type and 115 delivers fuel through the intake 46. The usual form of inwardly opening check valve 8' is present in the crank case 8.

The construction shown in Figs. 3 and 4 operates as follows:

In this construction the carburetor 45 is located at the intake 36' and the crank case 8 is utilized for pumping air only, and is provided with an air inlet valve 8' and with an air outlet valve 40. 125

The operation of the throttle valve 36, the stop 32, the levers 16 and 18 and the spring 26, is substantially the same as in the construction shown in Figures 1 and 2.

During operation under load conditions 130

therefore the vertical face of the member 37 prevents a movement of the valve stem 42 and thereby the opening of the valve 40 by the pressure in the crank case 8.

5 When, therefore, the throttle lever 16 engages the stop 32 by vertical movement of the rods 21 and 35 to throttle the engine, the bevel 39 of the member 37 permits a slight opening of the valve 40 and thereby a waste 10 of pressure in the crank case 8.

By permitting the crank-case outlet valve to open just before the lower dead center is reached the pressure in the crank case is relieved and a suction load placed upon the 15 piston; thus the engine is prevented from racing, that is, working against pressure in the crank case on the downward stroke and against a partial vacuum on the upward stroke.

20 Considerable variation of the details as described herein may be resorted to without

departure from the spirit of the invention which is to be construed in the light of the following claim.

Having thus described my invention what 25 I claim as new and desire to secure by Letters Patent is:

The combination with a two-cycle internal combustion engine having a cylinder and crank case, of means to supply an efficient charge of fuel thereto when idling, of means to compress air or an explosive mixture in the crank case thereof, means to admit a portion of said air or mixture to the cylinder thereof, and means to permit 30 the release from said crank case of a portion of said air or mixture, for the purpose set forth.

In testimony whereof I affix my signature hereto.

DAVID L. WINTERS.
